ROCKING CHAIR

Dale D. Smith, Irvine, Calif., assignor to
Samsonite Corporation, Denver, Colo.

Filed Jan. 2, 1974, Ser. No. 430,169

Term of patent 14 years

Int. Cl. D6—01

U.S. Cl. D6—49

FIG. 1.

FIG. 2.

FIG. 3.

FIG. 4.

FIG. 1 is a perspective view of a rocking chair, showing my design;

FIG. 2 is a rear view thereof;

FIG. 3 is a plan view; and

FIG. 4 is a side elevational view.

The side opposite to that shown in FIG. 4 has the appearance of that shown in FIG. 4.

I claim:

The ornamental design for a rocking chair, as shown and described.
